TELEVISION TUNER

Rudolf Wm. Selbmann, Jamaica, Morris L. Tucci, Brooklyn, and Walter Piwinski, Westbury, N. Y., assignors to Oak Mfg. Co., a corporation of Illinois

Application January 10, 1955, Serial No. 480,918

3 Claims. (Cl. 250—40)

This invention relates to a television tuner and more particularly to a tuner of the rotary switch type. As is well known, such a tuner comprises a number of rotary switch sections associated with suitable index means so that the switch may be turned to any one of a number of different positions. The switch sections carry suitable circuit components such as inductors, capacitors and resistors so that suitable resonant circuits for particular television channels are provided for each indexed switch position. Thus as an example, switch sections as illustrated in United States Patent No. 2,186,949 issued on January 16, 1940, may be used.

This invention provides a construction whereby the size of the tuner may be reduced and simplified. In addition, this invention provides a novel construction for a trimmer or vernier condenser used for fine tuning.

In order that the invention may be understood, reference will now be made to the drawing wherein an exemplary embodiment illustrative of the invention is shown. It is understood, however, that variations may be made without departing from the scope of the invention except as defined by the appended claims.

Figure 1 is a perspective view with certain parts broken away showing a tuner embodying the present invention.

Figure 2 is an end view with certain parts broken away of the tuner illustrated in Figure 1.

Figure 3 is an exploded view of the trimmer condenser and drive.

Figure 4 is a sectional detail on line 4—4 of Figure 1.

The tuner comprises relatively heavy metal housing generally indicated by 10 and having a generally U shape. While it is possible to make housing 10 of one piece, it is convenient to have part 11 and rear panel 12 in one piece with front plate 13 separated from but rigidly attached to part 11 as by bolts, spot welding, or the like. Part 11 of the housing functions as a tube shelf upon which some vacuum tube amplifiers and other components may be supported. Housing 10 is provided at the bottom with metal reinforcing bar 15 extending across from the front to the rear panels and rigidly attached to the bottom edges of such panels.

Suitably journaled in plates 12 and 13 is shaft 17. Shaft 17 extends through a number of switch sections generally indicated by 19, such switch sections having stator and rotor parts.

Each switch section includes a stator 21 formed of insulating material carrying stationary contacts 22 and circuit elements as inductors 23. Stationary contacts 22 are flat strips of metal having spaced radial slots 24 and carrying attached thereto as by eyelets 25 spring contact clips 26. Suitable adjusting screws, coils, and the like are secured to the various stationary contacts as illustrated in the drawing. Inasmuch as the details of the switch section form no part of the present invention, a detailed description thereof will not be given.

Forming part of each switch section is rotor 30 carried on the shaft and having suitable rotor contacts 31

for cooperation with the stator contacts. Thus rotor contacts 31 generally take the form of flat strips of metal designed to cooperate with any desired stationary contact or contacts for switching purposes. The rotor for a switch section includes an insulating disc carrying the rotor contacts, the insulating disc having a non-circular aperture therethrough for coupling to the shaft so that the shaft may rotate the rotor disc. The rotor contacts move between the opposed jaws of the spring contact clips.

Each switch section 19 has stator 21 thereof shaped to provide top and bottom wings 32 and 33. These wings extend through slots in tube shelf 11 and reinforcing bar 15 and are tightly wedged therein. By virtue of this arrangement, a rigid support for each switch section is provided.

In practice, a complete television tuner may have as many switch sections as are necessary for proper operation, there usually being at least four and sometimes there being as many as five switching sections. Some switching sections are shielded from the remaining sections as by a metal plate 35 disposed between rear and front panels 12 and 13 respectively.

Any suitable index means for permitting the switch to be indexed from one position to the other is provided, such index means being secured on the shaft and on one of the panels, such as for example on the inside of front panel 13. As an example, spring arm 36 attached to shaft 17 carries ball bearing 38 which is pressed against the inside surface of panel 13. Panel 13 has a number of apertures 39, smaller than the ball bearing, for defining an index position. It is understood that the switching sections are so designed that each index position corresponds to a different switch position.

35 Fine tuning means are provided, such means consisting of two fixed condenser plate electrodes having a movable dielectric therebetween. The dielectric is so selected as to have a high specific dielectric constant so that movement of the dielectric with respect to the electrodes will result in variation of capacitance.

While the stator portions of switch sections consist of a simple piece of insulation having two wing portions, the end stator near one of the housing panels as panel 13 is shaped to have an additional support portion 41.

45 Stator support portion 41 carries one plate 42 of a condenser. While plate 42 may have any desired shape, the construction illustrated has been found to be satisfactory. This comprises electrode portion 43 and three bent supporting portions 44. The supporting portions have small fingers 45 adapted to pass through slots in insulating stator portion 41. The fingers after passing through the stator portion are staked or spread to lock the condenser plate in position on switch stator portion 41.

Cooperating with condenser plate 42 is companion condenser plate 47 having an electrode portion and having mounting portions 48 and 49 provided with fingers 50 and 51. Fingers 50 and 51 pass through slots in front metal panel 13. The distance between the condenser electrode plates is set by a thickness gauge, after which plate 47 is rigidly secured in position by soldering or spot welding fingers 50 and 51 to front panel 13.

Dielectric plate 55 of suitable thickness is disposed between the condenser plates, the dielectric plate being carried in such manner as to be movable in and out of the region between the condenser plates. To this end dielectric plate 55 is carried by stub shaft 56 rotatively secured in part 57 of grounded cooperating condenser plate 47 and in front panel 13. As is clear from Figure 3, condenser plate 42 is shaped to clear the shaft. Dielectric plate 55 is suitably shaped so that upon turning of stub shaft 56, the dielectric plate will be moved in and out of the region between the opposing condenser plates.

It is understood that condenser plate 42 carried by stator portion 41 is connected in the oscillator section of the tuner so that the capacitance of the trimmer condenser will result in varying the frequency of the oscillator to tune in the desired channel.

Means for varying the trimmer condenser are provided, such means including a general sector shaped plate 60 attached to stub shaft 56. Finger 51 of the grounded condenser plate is long enough so that it may be engaged by suitably shaped parts of sector plate 60 to function as a stop and limit the rotation of this plate. Sector plate 60 extends toward tuner shaft 17. Control of fine tuning is obtained by a pair of spring friction washers 63 and 64 carried by sleeve 65 disposed on shaft 17. The sleeve may be longitudinally locked to shaft 17 by spring wire 67 disposed in a slot in the sleeve and cooperating with an annular groove in shaft 17. Friction washers 63 and 64 are on opposite sides of the edge of sector plate 60 and provide a friction drive between sleeve 65 and the trimmer condenser stub shaft. Suitable knobs on the tuner shaft and sleeve may be provided and the tuner shaft knob may cooperate with indicator means for showing the selected channel.

The fine tuning trimmer condenser may be disposed adjacent the rear panel of the tuner housing. In such case, the sleeve over the shaft would be used to operate the switch sections and the solid shaft would carry friction discs or washers for fine tuning.

What is claimed is:

1. In a rotary switch type tuner for high frequencies, said tuner including a rigid metal housing having parallel front and rear metal panels, a shaft rotatively secured in said front and rear metal panels and passing through the housing, a plurality of switch sections within said housing, each switch section including an insulating stator, means for rigidly supporting each stator in said housing, each stator having a cooperating rotor engaged by the shaft passing through the same, the end stator nearest the front panel carrying a fixed condenser plate having an electrode portion lying in a plane generally parallel to said panel, a cooperating fixed condenser plate carried by said front panel and having an electrode portion disposed parallel to and spaced from said first named condenser plate, a stub shaft journaled for rotation in the front panel and in the cooperating condenser plate, a dielectric plate carried by said stub shaft and movable thereby between the condenser plates for varying the capacitance thereof, the entire condenser lying within the metal housing, means disposed on the outside of the front panel for turning the stub shaft to vary the capacitance, said end insulating stator adjacent the front panel having oppositely disposed extensions secured to said housing and having a third extension secured to said housing with said fixed condenser plate secured to said third extension so that the same is retained rigidly in position.

2. In a rotary switch type tuner for high frequencies, said tuner including a rigid metal housing having parallel front and rear metal panels, a shaft rotatively secured in said front and rear panels and passing through the housing, a plurality of switch sections within said housing, each switch section including an insulating stator, means for rigidly supporting each stator in said housing, each stator having a cooperating rotor engaged by the shaft passing through the same, the end stator nearest

the front panel carrying a fixed condenser plate having an electrode portion lying in a plane generally parallel to said panel, a cooperating fixed condenser plate carried by said front panel and having an electrode portion disposed parallel to and spaced from said first-named condenser plate, a stub shaft journaled for rotation in the front panel and in the cooperating condenser plate, a dielectric plate carried by said stub shaft and movable thereby between the condenser plates for varying the capacitance thereof, the entire condenser lying within the metal housing, means disposed on the outside of the front panel for turning the stub shaft to vary the capacitance, said front panel being apertured and the cooperating condenser plate having fingers extending through said front panel and soldered thereto, said cooperating condenser plate being adjusted with respect to the front plate to provide a predetermined separation from the fixed condenser plate prior to soldering, the separation being equal to the thickness of the dielectric plate.

3. In a rotary switch type tuner for high frequencies, said tuner including a rigid metal housing having parallel front and rear metal panels, a shaft rotatively secured in said front and rear metal panels and passing through the housing, a plurality of switch sections within said housing, each switch section including an insulating stator, means for rigidly supporting each stator in said housing, each stator having a cooperating rotor engaged by the shaft passing through the same, the end stator nearest the front panel carrying a fixed condenser plate having an electrode portion lying in a plane generally parallel to said panel, a cooperating fixed condenser plate carried by said front panel and having an electrode portion disposed parallel to and spaced from said first-named condenser plate, a stub shaft journaled for rotation in the front panel and in the cooperating condenser plate, a dielectric plate carried by said stub shaft and movable thereby between the condenser plates for varying the capacitance thereof, the entire condenser lying within the metal housing, means disposed on the outside of the front panel for turning the stub shaft to vary the capacitance, said cooperating condenser plate including a number of fingers passing through apertures in the front panel, said cooperating condenser plate being soldered to said front panel after the plate has been disposed in desired position, one of the fingers of said cooperating condenser plate extending through the front panel and functioning as a stop finger, a sector disc carried by said stub shaft and having a portion shaped to cooperate with said stop finger for defining a range of angular travel of said stub shaft, a sleeve disposed over said tuner shaft and friction discs on said sleeve and engaging said sector disc on opposite sides thereof at the edges thereof for driving the same.
